UNITED STATES PATENT OFFICE.

JOHN M. FITZ GERALD, OF RIVER FOREST, ILLINOIS.

TERMINAL DEVICE.

Application filed December 16, 1921. Serial No. 522,764.

To all whom it may concern:

Be it known that I, JOHN FITZ GERALD, a citizen of the United States, residing at River Forest, Cook County, State of Illinois, have invented certain new and useful

Improvements in Terminal Devices, of which the following is a specification.

The present improvements relate to terminal devices adapted to receive the projecting ends of cables or other electrical conduit wires and which are, for their greater part, buried in the ground or otherwise concealed. Such devices are ordinarily known as "pot heads" in the art, and their general object is to provide means for housing projecting ends of such wires close to the ground or where they otherwise emerge whereby access may be had to these ends for connecting or disconnecting them to each other or for tapping into them, upon removing a cover of the device.

The principal specific objects of the present improvements are to provide a terminal device of the class referred to which is sus-

ceptible of use with free cables or wires issuing from the ground, trunking box, etc., or for cables encased by pipes of various diameters, as where such pipes issue from the earth or from a concrete or other structure;

one in which the wires may be held securely by means independent of the electrical connections, thus saving those connections from disruptive strains; one in which the cable, free wires or tubing are so arranged that a

sealing compound such as is commonly used in the art may be readily applied to such parts so as effectively to prevent moisture from finding its way along the wires, into the pipes, or into the insulation; one in

which the connection elements may be of simple form, conveniently arranged and readily available for manipulation; one in which tapping wires may be carried to the interior of the device and se-

cured to connection elements in a simple and easy manner and without prejudice to the substantially tight character of the housing as a whole; one in which a sealing com-

pound may readily be applied so as effectively to secure all of the parts within the device against the corrosive and otherwise injurious effect of moisture; one according to which the various parts may be assembled easily and progressively at the time of in-

stallation whereby notable freedom and con-

venience of operation may be had as the work of installation goes along; and, in general, a device of strong and simple construction which is highly effective to provide the desired results.

In the accompanying drawings, which form a part of this specification, Figure 1 is a top plan of my improved device in a preferred construction and arrangement; with the cover part broken away; Fig. 2 is a medial vertical section, as on the line 2—2 of Fig. 1, of the device complete, with certain terminal wires extending thereinto; Fig. 3 is a top plan with parts removed showing the clamping members and the side wall structure; Fig. 4 is a horizontal sectional view as on the line 4—4 of Fig. 2; Fig. 5 is a medial vertical section as on the line 5—5 of Fig. 1; Figs. 6 and 7 are fragmentary top and side views of details; and Fig. 8 is a fragmentary medial section similar to that of Fig. 2 showing the use of the device with tubes in which the electrical wires are carried.

My improved terminal device includes first a base 10 which is preferably a plate-like member normally horizontally-disposed when the terminal wires issue upward.

It is shown as elliptical in contour and defines the general plan of the device. The base may be secured upon a pedestal or support 11 as by bolts 12, (Fig. 2) or, as shown in Fig. 8, where a conduit pipe as 13 issues from the ground the base 10 may be clamped between upper and lower binding nuts 14 and 15 threaded upon the pipe, or where a pipe as 16 issues from concrete the base 10 may be held securely by a nut 17 threaded upon the pipe.

The base 10 has an annular peripheral seat 20 adapted to receive with a substantially good fit the side wall or ring-like member 22, which has the same substantially elliptical contour and forms with the base 10 a cup-like structure which is part of the housing for the wires and connection parts. The side wall or ring-like member 22 is preferably made as a separate piece so that before it is applied the base may be easily positioned and other operations performed as the installation proceeds.

The base 10 is suitably in the form of an iron casting, and is shown as having a medial integral web or partition-like member 24 which extends transversely of the de-

vice, rises well toward the plane of the top of the side member 22 and contains a pair of vertically-extending recesses 25 adapted to receive, from the top, the bolts 26 respectively. Clamping nuts 27 hold each bolt 26 rigidly upon the upstanding projection 24 at any desired elevation. Each of the bolts 26 carries a pair of clamping bars 30 at one end portion and 31 at the other end portion, 10 nuts 32 and 33 being adapted to draw together the clamps at the respective end portions of the bolts.

Referring to Fig. 2 the terminal wires 34 are shown as entering the interior of the device in the form of a cable through an opening 35 in the base 10 and the clamping members 31 are shown in Figs. 2, 3 and 4 to be firmly clamped and bound upon the cable, the free end portion of the cable being thereby held rigidly by means within the housing independent of the electrical connections. The terminal wires 34 constituting the cable, when freed of outer cable wrappings, may severally then be applied to connection elements as desired without interference by the weight of the cable and, importantly, the tendency of the connections to become disrupted by the weight of the cable at a subsequent time is avoided. Figs. 2, 3 and 4 also show terminal wires 40 in a small cable similarly held by the clamps 30.

Where wires 41 or 42 (Fig. 8) issue from pipes they may similarly be clamped by the clamping means shown, the bunch of wires being first wrapped with lineman's tape or fabric if desired to bring its bulk up to a size suitable for clamping or to protect the insulation of the wires against the binding action of the clamps.

40 A feature of importance in this connection is that the base may first be positioned and then the terminal wires may be firmly clamped in a desired position, no other parts of the device being present at the time, thus giving the workman notable freedom in performing these operations.

The holding means for the wires will ordinarily be spaced materially from the base to allow full freedom for the assembling operations, as well as to provide space for sealing compound should it be desired to apply such compound upon the base and surrounding the cables, wires or ends of the pipes as 13 and 16 (Fig. 8), and in such case, to prevent the sealing compound from running into the open ends of the pipes or out through the holes 35 and 45 (Fig. 2) in the base 10 these openings may be closed as by a piece of cardboard 46 (Fig. 2), or by packing 47 (Fig. 2) of cotton waste or jute, or at 48 and 49 (Fig. 8). Such sealing compound would be applied in the lower chamber or space containing the free ends of the pipes and the clamping means only after the side member 22 has been put in place.

The ring-like side member 22 has a pair of facing projections 50 recessed (as well illustrated in Fig. 4) to receive lateral edge portions of the upright vane-like projection 24 of the base, the side member 22 being thus firmly stabilized upon the base. Each of these projections 50 has an overlying cover part 51 (Fig. 3) and screws 52 passing through them and threaded into the rib 24 (as well illustrated in Fig. 2) hold the side wall member firmly upon the base at the annular seat 20.

A plate-like piece of insulation 55 is held upon the side member 22 by screws 56 (Fig. 2) threaded into a projection 57, the upper surface of which is in the plane of an annular rib 58 defining the upper edge of the side member 22. From Figs. 2 and 5 it will clearly appear that the insulation 55 has an annular depending flange 59 overlying this projection 58, the insulation not only thereby being held firmly in its desired position, but the overlapped relation of the parts 58 and 59 provides a wall against the entrance there of moisture which might under some conditions enter at the cover connections adjacent thereto.

The insulation block or plate 55 has a pair of relatively large openings 60 and 61 through which terminal wires such as 34 and 40 may pass whereby the free and stripped ends of these wires may be above the block of insulation 55. The top surface of the insulation 55 is provided with a plurality of terminal posts 63 arranged around the openings 60 and 61, and a plurality of other terminals 64 arranged at otherwise open spaces, these terminal posts being insulated from each other and each being provided with clamping nuts 65, such posts and nuts providing a well-known form of electrical connection. With such an arrangement it is clear that any two wires coming into the terminal device may be connected together by means of a single binding post or two binding posts may be connected by a short wire.

A feature of importance in this connection is in the fact that the electrical connections may be made and from time to time changed and inspected as desired in a simple and easy way upon removing the cover of the device. In practice the various connection elements may be numbered, as by an imprint in the porcelain, so that a written record may be made showing how the several wires are connected.

It is frequently desirable in the use of a device of this kind to tap into one or more of the lead wires for some special purpose either at the time of installation or after the original installation has been made. Figs. 1, 2, 3 and 5 clearly show that the annular flange 70 extending laterally from the side member 22 is considerably wider

on the short axis of the substantially elliptical figure than on the long axis thereof, thus providing space for a considerable number of outlet openings 71 (Figs. 5 and 7) without unnecessarily extending the device on its longer axis. These openings 71 in the flange 70 are on tapered lines, as well shown in Fig. 7, and as shown in Fig. 5 they lead from the inside to the outside of the device. Figs. 6 and 7 show how lead wires connected to the terminals 64 (or any other terminal desired) may be carried through the openings 71 without impairing the security of the inside of the device against moisture, and so as to hold the wires firmly by means independent of the electrical connections. I provide, preferably for two openings 71, a single plate 73 held by a middle screw 74, each plate having openings 75 registering with the openings 71 respectively but smaller than the openings 71 at the top, whereby packing material 76, such as lineman's tape may be wrapped around the conductor there and by means of the plate 73 compressed tightly about the conductor, making the joint water tight and binding the wire in a given position. For closing an opening 71 a cork stopper 77 may be forced into the hole and maintained in place by the over-lying plate 73 (Fig. 7).

The cover 80 has a depending flange 81 deeply overlying the horizontal flange 70 of the side member, the cover having an annular shoulder at 82 resting upon the flange 70, the cover thus providing a good protection for the interior construction and wires against the weather. Nuts 84 on bolts 85 (Fig. 2) act as stops to prevent the cover from being removed, while providing readily operable means for releasing the cover when desired.

Referring to Fig. 2 it will be noted that the upper ends of the cables where their wrappings are removed are above the clamping means and below the insulating plate 55. It is not strictly essential that such exposed parts of the cable shall be in that location, but that arrangement provides that when a piece of cardboard, thin metal or any other suitable material forming a wall or obstruction, as the sheet 86 (Fig. 2), is applied so as to cover the clamping means, the space above this sheet 86 and below the insulation 55 may be flowed full of the sealing compound ordinarily used for such purposes, and as indicated by the stippling of Figs. 2 and 5 at the place mentioned, thus sealing the interstices of the cables where the wires issue therefrom, and between various wrappings thereof, against the entrance of moisture. At the same time this sealing material makes a tight wall between the electrical connection elements on the insulation 55 and the openings 45 and 35 in the base 10 which prevents moisture or cor-

roding gases from the earth from passing into the chamber having the terminal connections.

In some instances, as in tunnels where the moisture may be excessive and in other situations where corroding gases are present in objectionable quantities it may be found desirable to apply the sealing compound throughout the interior of the device, from bottom to top, and in such case the partition 86 may be dispensed with and the entire bottom portion of the cup-like structure consisting of the base 10 and the side member 22 may be filled with the hot sealing compound before the insulating plate 55 is applied and the desired connections made, and thereupon, after the connections have been made and the cover 80 applied, the screw cap 90 at the top of the cover may be removed and the insulating compound poured therethrough until the upper portion also of the interior is filled. Thereafter, should it be desired to remove the cap or cover 80 the flame of a blow-torch may be applied to it until the compound within is softened. Upon removing the cover the sealing compound may be further melted or chipped away to expose the particular connections sought.

I contemplate as being within the present improvements various changes and departures in construction and arrangement from what is specifically herein illustrated and described, as indicated in the appended claims.

I claim:

1. In a terminal device of the character described, the combination of a normally horizontally-disposed base having an opening therethrough for terminal wires, a projection upstanding rigidly from the base, clamping means carried by said projection for holding such terminal wires rigidly, means forming a side wall of the device upstanding from said base, and cover means readily removably secured upon said base.

2. In a terminal device of the character described, the combination of a normally horizontally-disposed base having an opening therethrough for terminal wires, said base having an upstanding projection, clamping means carried by said projection for holding such terminal wires, a ring-like side member resting upon said base, insulation carried by said ring-like member above said clamping means, a plurality of terminal connections carried by said insulation, and a cover member resting upon said ring-like member and readily removably secured thereto.

3. In a terminal device of the character described, the combination of a normally horizontally-disposed base having an opening therethrough for terminal wires, a ring-like side member upstanding from said base,

a cover member upon said ring-like member, insulation carried by the device, a plurality of terminal connections carried by said insulation, mechanical means for holding end 5 portions of terminal wires against retraction from the device, and means normally above said mechanical means for holding a layer of sealing compound adapted to imbed portions of such terminal wires, the 10 arrangement being such that by removing the cover member access may be had to said terminal connections.

4. In a terminal device of the character described, the combination of means forming a cup-shaped structure having a bottom part normally horizontally disposed with an opening therethrough for terminal wires, means carried by said structure for holding said terminal wires rigidly, insulation in 15 plate-like form carried by said structure and positioned above said clamping means, a plurality of terminal connections carried by said insulation, means between said clamping means and said terminal-wire-holding means for holding sealing compound so as to imbed portions of such ter- 20 25

minal wires and form a layer of such sealing compound between the side walls of said cup-shaped structure, and a cover readily removably held upon said structure, the whole forming a receptacle for the clamping means, terminal connections, sealing compound and insulation. 20

5. In a terminal device of the character described, the combination of a cup-shaped structure having bottom and side walls, the side walls having an outwardly-extending flange, said flange having an opening there- 35 in for terminal wires, the bottom wall having an opening for terminal wires, means 40 within said structure for holding terminal wires firmly against retraction, insulation in plate-form substantially occupying the upper area of said cup-shaped structure and carried thereby, there being an open- 45 ing for terminal wires through said insula- tion, a plurality of terminal connections on the upper surface of said insulation, and a cover member readily removably carried by said structure, said cover protectively over- 50 lying said flange.

JOHN M. FITZ GERALD.
